**HOUSING FOR ELECTRONIC SIGNAL
PROCESSOR OR THE LIKE**James A. Dalke, Seattle, Wash., assignor to
MetroData Corporation, Seattle, Wash.

Filed Aug. 25, 1971, Ser. No. 175,043

Term of patent 14 years

Int. Cl. D13—03

U.S. Cl. D26—5 R

*Fig. 1*4,324,678

*Fig. 2*Fig. 3

Fig. 4

Fig. 5

Fig. 6

Fig. 7

FIG. 1 is a front perspective view of a housing for electronic signal processor or the like showing my new design;

FIG. 2 is a rear perspective view thereof;

FIG. 3 is a front elevational view thereof on a reduced scale;

FIG. 4 is a left side elevational view thereof on a reduced scale;

FIG. 5 is a right side elevational view thereof on a reduced scale;

FIG. 6 is a top plan view thereof on a reduced scale;

FIG. 7 is a rear elevational view thereof on a reduced scale.

The switches, knobs and electric cord are shown in broken lines for illustrative purposes only.

I claim:

The ornamental design for a housing for electronic signal processor or the like, as shown and described.
